ANGULARLY ADJUSTABLE, REVERSIBLE RATCHET WRENCH

Roy C. Hopgood, Glen Ridge, N. J., assignor to The New Britain Machine Company, New Britain, Conn., a corporation of Connecticut

Application October 1, 1953, Serial No. 383,590

7 Claims. (Cl. 81—61)

My invention relates to flexible, universal-action ratcheting devices, particularly applicable as socket-wrench tools and sometimes known as flexratchets. The invention incorporates improvements and modifications over the structure disclosed in Karl E. Queitzsch Patent No. 2,660,911, and over the construction shown in Eugene M. Fruscella application, Serial No. 383,589, filed on even date herewith.

It is an object of the invention to provide an improved device of the character indicated.

Another object is to provide a ratchet wrench of the character indicated, requiring fewer parts and thus costing less to manufacture.

A specific object is to meet the above objects with a construction in which one-way ratchet action can be reversed without requiring relative movement of ball-retaining parts.

Another specific object is to provide a ratcheting device of the character indicated in which the freedom for wrench action exceeds 90 degrees of angular adjustment of the handle axis with respect to the tool-actuating axis.

Other objects and various further features of novelty and invention will be pointed out or will occur to those skilled in the art from a reading of the following specification in conjunction with the accompanying drawings. In said drawings, which show, for illustrative purposes only, a preferred form of the invention:

Fig. 1 is a view in longitudinal elevation of a flexible ratcheting device incorporating features of the invention;

Fig. 2 is an enlarged, fragmentary, sectional view taken in the plane 2—2 of Fig. 1;

Fig. 3 is another sectional view taken in the plane 3—3 of Fig. 1;

Figs. 4 and 5 are fragmentary sectional views taken in the plane 4—4 of Fig. 3, but respectively showing the tool-actuating tang displaced to its two limits of angular adjustment; and

Figs. 6 and 7 are fragmentary, sectional views in the planes 6—6 and 7—7, respectively, of Figs. 4 and 5.

Briefly stated, my invention contemplates achievement of reversible ratchet action in flexible ratchet devices (as described in the above-identified copending applications) by eliminating certain parts which have previously required relative movement of the ball retainer or cage with respect to the handle in order to achieve reversal of ratchet action. With my device, ratchet action may be reversed by merely providing a longer arcuate slot for the tool-attachment tang, the length being sufficient to permit selective placement of the tool-attachment tang, on one side or on the other side of the handle axis, as desired.

Referring to the drawings, my invention is shown in application to a ratchet tool comprising an elongated handle 10, one end of which may be provided with ball-retaining means in the form of an enlarged head 11. The head or cage 11 may be formed integrally with the handle, but, for simplicity of manufacture, I have shown cage 11 as a separate piece secured, as by welding (suggested at 12), to the enlarged end 10' of handle 10. For

2

tool-actuating purposes, a tang 14 may be integrally formed out of or carried by a free-swiveling ball 15 retained within the cage 11. The tang 14 may be squared or otherwise formed for adaptation to standard tools, such as socket wrenches, and may be connected to the ball 15 by means of a reduced shank 16 accommodated in an arcuate slot 17 in the cage 11. For improved support and retention of the ball 15, the enlarged end 10' of the handle may be spherically recessed at 18 (Fig. 2) and thus embrace a major lower area of the ball 15.

Pawl means 19 having a thrust-sustaining axis substantially normal to the plane including the slot 17 and the handle axis, may be carried by the handle and urged as by spring means 20 for constant engagement with the ball 15; spring means 20 is shown located in a small axial bore 13 within the end 10' of handle 10. In the form shown, the pawl and ratchet engagement is accomplished as a toothed engagement, the ball 15 being provided with a plurality of teeth 21 cut generally as great-circle arcs in planes passing through the axis of the tang 14 and shank 16.

The described parts are essentially those shown in the said Fruscella application, and the action is essentially the same. Thus, in the straight-on orientation of the tang 14 shown in Fig. 2, the pawl 19 may ride a flat 22 on ball 15 and thus have no ratcheting engagement with the ball 15. For this orientation, the width of the slot 17 may be slightly reduced by the formation of locally protruding wall elements 23 to accommodate the squared section of shank 16, as is best shown in Fig. 3. For this orientation, therefore, the handle will be locked to the tang 14, and no ratcheting action will take place.

In accordance with the invention, the slot 17, which in said other applications merely extends from the straight-on position to one side only of the handle axis, is now caused to extend to the other side of said axis; in the case shown, the slot 17 is of sufficient arcuate extent to accommodate placement of the tool-actuating tang as far as 90 degrees to one side of the handle axis, as shown in Fig. 4, or if desired, as far as 90 degrees to the other side of said axis, as shown in Fig. 5.

It will be seen that universal ratcheting action may be achieved, not only for the extreme positions of Figs. 4 and 5, but also for most intermediate angular orientations of the tang 14 with respect to the handle 10, except those close to the straight-on position. For placements of the tang 14 on the side of the axis of the handle 10 shown in Fig. 4, ratchet engagement will be developed from the relation shown in Fig. 6; for this relation, the ratchet 50 will escape for counter-clockwise movement of the handle 10 with respect to the ball 15 and tang 14, but will drive the ball and tang for clockwise movement of the handle 10 about the tang axis, regardless of whether the tang axis is at the extreme 90-degree position with respect to the handle axis, or whether it lies at some reduced angle, except of course near the straight-on position discussed above. For adjustments of the tang to the other side of the handle axis (depicted in Fig. 5), the pawl 19 will have been effectively reversed with respect to the drive axis, so that, as clearly shown in Fig. 7, the pawl will escape for clockwise movement of the handle with respect to the ball 15 and will drive for counterclockwise movement of the handle with respect to the ball.

It will be noted that, by suitably accommodating the over-all width of the ratchet tooth of pawl 19 to the effective span of the flat 22 on ball 15, the pawl 19 and flat 22 may cooperate for the straight-on position shown in Fig. 2 to serve a detent function, resiliently retaining the parts in this relationship. This detent action will be found useful when it is desired to operate the device in the lock-up straight-on condition.

It will be seen that I have described a relatively simple

3

construction, which may be particularly attractive from the point of view of requiring fewer parts than previous constructions. Regardless of the fewer parts, reversible ratchet action is readily selected merely by flipping the tang to a particular side of the handle axis, and the universality of ratchet action is, if anything, extended over that in previous constructions.

While I have described the invention in detail for the preferred form shown, it will be understood that modifications may be made within the scope of the invention as defined in the claims which follow.

I claim:

1. In a ratcheting device of the character indicated, a handle including a ball-retainer cage fixedly carried thereby, said cage having an arcuate slot therein, ratchet means including a ball movably retained by said cage and fixedly carrying a tool-driving tang projecting generally radially of said ball and through said slot, one-way engaging pawl means retained by said handle and engageable with said ball, said pawl means having a thrust-receiving axis oriented substantially normal to the general plane of movement of said tang in said slot, and said slot being sufficiently elongated on either side of said axis to permit one-way ratchet engagement selectively on one side of the axis of said tang or on the other side of the axis of said tang upon merely shifting the axis of said tang in said slot.

2. In a device of the character indicated, universal reversible-ratchet tool-actuating means, comprising a frame including a ball-retaining cage and having an arcuate slot therein extending effectively 180 degrees on a great circle of the ball-retaining center and symmetrically on both sides of a longitudinal axis of said device, a ball freely rotatable in and retained by said cage and including a tool-attaching tang projecting radially with respect to the axis of said ball and through said slot, and one-way-engaging pawl means acting between said ball and said frame and having a fixed uni-directional thrust-sustaining axis transverse to the general plane of said slot.

3. In a device of the character indicated, a handle and a ball-retaining cage fixedly carried at one end of said handle, said cage having an arcuate slot on the axis of said handle and extending substantially in a single arc on both sides of said axis, a ball rotatably retained by said cage and including a radially projecting tool-adapting tang extending through said slot, arcuate ratchet teeth on said ball and extending generally in great-circle paths, each said path being substantially in a plane including the axis of said tang, a ratchet pawl carried by said handle and spring-urged for one-way engagement with said teeth, said pawl being retained by said handle at a location on the other side of said ball with respect to the center of symmetry of said slot.

4. In a device of the character indicated, a handle including a ball-retaining cage fixedly carried at one end of said handle, said cage having an arcuate slot on the axis of said handle and extending substantially in a single arc on both sides of said axis, a ball rotatably retained by said cage and including a radially projecting tool-driving tang extending through said slot, arcuate ratchet teeth on said ball and extending generally in great-circle paths, each said path being substantially in a plane including the axis of said tang, a ratchet pawl carried by said handle and spring-urged for one-way engagement with said teeth, said pawl engaging said ball substantially on the axis of said handle, and said ball being cut off substantially transverse to the axis of said tang and on the side of said ball remote from said tang, whereby said

4

pawl may cooperate with the cut-off part of said ball to provide detent retention of the straight-on orientation of said tang with respect to the handle axis.

5. In a device of the character indicated, a handle including a ball-retaining cage fixedly carried at one end of said handle, said cage having an arcuate slot on the axis of said handle and extending substantially in a single arc on both sides of said axis, a ball rotatably retained by said cage and including a radially projecting tool-driving tang extending through said slot, a ratchet pawl carried by said handle and spring-urged for one-way engagement with said ball, said pawl engaging said ball substantially on the axis of said handle, and said ball being cut off substantially transverse to the axis of said tang and on the side of said ball remote from said tang, whereby said pawl may cooperate with the cut-off part of said ball to provide detent retention of the straight-on orientation of said tang with respect to the handle axis.

10 6. In a device of the character indicated, a handle and a ball-retaining cage fixedly carried at one end of said handle, said cage having an arcuate slot on the axis of said handle and extending substantially in a single arc on both sides of said axis, a ball rotatably retained by said cage and including a radially projecting tool-adapting tang extending through said slot, arcuate ratchet teeth on said ball and extending generally in great-circle paths, each said path being substantially in a plane including the axis of said tang, a ratchet pawl carried by said handle and spring-urged for one-way engagement with said teeth, said pawl being retained by said handle at a location on the other side of said ball with respect to the center of symmetry of said slot, the end of said pawl opposite the tang-projecting end thereof being locally flattened, whereby said pawl may ride the flattened area and thus provide a detent-retaining function for said tang for one orientation of said pawl in said slot.

15 7. In a device of the character indicated, a handle and a ball-retaining cage fixedly carried at one end of said handle, said cage having an arcuate slot on the axis of said handle and extending substantially in a single arc on both sides of said axis, a ball rotatably retained by said cage and including a radially projecting tool-adapting tang extending through said slot, arcuate ratchet teeth on said ball and extending generally in great-circle paths, each said path being substantially in a plane including the axis of said tang, a ratchet pawl carried by said handle and spring-urged for one-way engagement with said teeth, said pawl being retained by said handle at a location on the other side of said ball with respect to the center of symmetry of said slot, said tang having a substantially square cross-section adjacent said slot, and the width of said slot at the location substantially in line with the axis of said handle being reduced to receive said squared section and lock the same against rotation.
